UNITED STATES PATENT OFFICE.

ABRAHAM POLLAK, OF NEW YORK, N. Y., ASSIGNOR TO SAMUEL KANNER, OF NEW YORK, N. Y.

LEAD PENCIL.

Application filed November 24, 1924. Serial No. 751,795.

The invention relates to improvements in mechanical lead pencils of the magazine type, and it consists in the novel features, arrangements and combinations of parts hereinafter described, and particularly pointed out in the claims.

One object of the invention is to provide a lead pencil capable of holding in an upper magazine chamber a number of sticks of lead adapted for use in the pencil and of automatically feeding the same, one at a time, to the mechanism, by which the individual sticks of lead are projected for writing purposes.

15 A further object of the invention is to provide in a lead pencil of the magazine type efficient means for feeding forwardly the individual sticks of lead without danger of breaking the same and which mechanism will permit a projecting piece of lead to be pushed back into the pencil.

20 A further purpose of the invention is to provide means for propelling the individual sticks of lead in such manner that a short piece of lead unsuitable for further use, is discharged from the pencil by the succeeding stick of lead following it into the operating mechanism of the pencil.

25 A further purpose of the invention is to provide a pencil of the type described in which the interior mechanism intended to grip the stick of lead is adapted to have a reciprocating plunger-like movement, in one direction or forwardly by the pressure 30 of the finger on the exterior cap of the pencil and in the other direction or rearwardly by an interposed spring concealed within the pencil, the gripping mechanism being adapted to slide rearwardly free of the stick 35 of lead and when pressed forwardly being adapted to grip the stick of lead and move the same forwardly.

40 The invention will be fully understood from the detailed description hereinafter presented, reference being had to the accompanying drawings, in which:

45 Fig. 1 is a central vertical section through a lead pencil embodying my invention, the interior mechanism of the pencil being shown in its outer or rear position, with the stick of lead gripped between opposing members and ready to be thrust forwardly to writing position when the interior mechanism is pressed forwardly in opposition to the force of the enclosed spring;

50 Fig. 2 is a corresponding view on a larger scale and partly broken away, showing the opposite position of the interior mechanism of the pencil, such mechanism having been pressed forwardly to eject the stick of lead for writing purposes and having released the stick of lead preparatory to being moved to its first or rear position by the enclosed spring;

55 Fig. 3 is a view corresponding with Fig. 2, but illustrating the interior mechanism of the pencil as receding rearwardly but as not having fully reached the position in which the parts are shown in Fig. 1;

60 Fig. 4 is a transverse section on a larger scale through the pencil, taken on the dotted line 4-4 of Fig. 1;

65 Fig. 5 is a corresponding view through the same, taken on the dotted line 5-5 of Fig. 1;

70 Fig. 6 is a corresponding view through the same, taken on the dotted line 6-6 of Fig. 1;

75 Fig. 7 is a corresponding view through the same, taken on the dotted line 7-7 of Fig. 1;

80 Fig. 8 is a detached central vertical section through the outer casing of the lead pencil;

85 Fig. 9 is a corresponding section through the cap of the pencil;

90 Fig. 10 is a side elevation of the forward pencil tip shown detached from the pencil;

95 Fig. 11 is a side elevation of the assembled interior mechanism of the pencil and which mechanism is to be inserted into the outer casting shown in Fig. 8;

100 Fig. 12 is a vertical section on a larger scale and partly broken away, through the lower end portion of the magazine for holding the supply of sticks of lead;

105 Fig. 13 is a central vertical section through the nut positioned at the lower end of the spring shown in Fig. 11;

110 Fig. 14 is a central vertical section through a sleeve having a conical bore and which is enclosed and longitudinally movable within the member shown at the lower end of Fig. 11 and also in Fig. 16;

115 Fig. 15 is a central vertical section through a collet constituting a portion of the interior mechanism and whose upper end is screwed into the base member of the magazine shown in Fig. 12 and whose lower end is confined within the chamber of the

member shown in Fig. 16 and at the lower end of Fig. 11, the coiled spring shown in Figs. 1, 2, 3 and 11, being arranged to encircle this collet between the lower end of 5 the said magazine and the nut shown in Fig. 13, positioned at the upper end of the member shown at the lower end of Fig. 11;

Fig. 16 is a corresponding view of a fitting constituting a portion of the connected 10 interior mechanism of the pencil and adapted to firmly seat within the conical forward or tip end of the outer casing of the pencil, and

Fig. 17 is a perspective view of the pencil. 15 In the drawings 20 designates the exterior cylindrical casing of the pencil, 21 a cap capable of reciprocating movement on the outer or rear end of said casing and 22 a conical section formed on the forward end 20 of the casing 20.

The interior mechanism of the pencil comprises the parts shown in Figs. 11 to 16 inclusive, plus the tip 23 having the threaded stem 24 shown in Fig. 10, which is finally, 25 in the assembly, connected with said interior mechanism.

The interior mechanism of the pencil, commencing at the outer or rear end of the same, comprises a sleeve 25 (Figs. 1 and 11), 30 a magazine tube 26 secured at its outer end within the lower portion of said sleeve, a base member 27 (Figs. 1, 2, 3, 11 and 12) secured to the lower end of said magazine tube and whose upper surface is of inverted 35 conical formation, as at 28, and constitutes the lower floor of the magazine and supports the series of reserve leads 29 shown in Fig. 1, a collet 30 whose upper threaded end is screwed into the threaded socket 31 of the 40 base member 27 and whose tubular interior is in line with a hole or bore 32 extending downwardly, for the passage of the leads, from the floor 28 of the lead-magazine, a coiled spring 33 on the collet 30 and engaging 45 at its upper end the aforesaid base member 27, a nut 34 against which the lower end of said spring 33 presses and which is screwed into the upper end of a tubular fitting or section 35 which closely seats within 50 the forward conical portion of the main casing 20, and a sleeve 36 (Fig. 14) which is vertically slidable within the chamber 37 of the tubular fitting or section 35 or between the lower end of the nut 34 and an 55 annular shoulder 38 formed within and on said section 35. The lower portion of the collet 30 is within the chamber 37 of the tubular fitting or section 35, and the sleeve 36 encompasses the collet 30 within said 60 chamber 37. Below the chamber 37 an auxiliary chamber 39 is formed in the tubular section 35, said chamber 39 being concentric with and of less diameter than the chamber 37, whereby the shoulder 38 is 65 formed. A threaded opening 40 extends

through the lower end of the tubular section 35, said opening being concentric with the chambers 39, 37 above it, and into this threaded opening 40 is screwed the tubular stem 24 of the tip 23, shown in Fig. 10. 70 The tip 23 comprises the tubular threaded stem 24, and a lower clutch member 41, at the upper edge of which is formed a shoulder 42 which engages the lower edge of the conical section 22 of the exterior casing 20. 75 The tip 23 is split vertically in its clutch section 41 and is adapted to grip the stick of lead which may be projected into it, but the gripping action of the clutch 41 is such as not to interfere with the forward propulsion of the stick of lead or in the return of the stick of lead into the pencil at such time as it may be desired to press the lead back into the pencil. The purpose of the clutch member 41 is to hold the stick of lead firmly 80 while the pencil is used for writing purposes and to prevent the stick of lead from slipping entirely from the lead pencil at such time as the propelling gripping mechanism contained within the pencil is free of the 85 lead.

The details of the exterior casing 20 will be apparent from an inspection of Fig. 8, said casing being a plain tube having at its lower end the conical section 22 which is 90 open at its lower end.

The cap 21 is a plain elongated tubular cap closed at its outer end and adapted to have sliding movement on the outer end of the exterior casing 20, being pressed downwardly on said casing by the finger of the user of the pencil and moved in a reverse direction or rearwardly by the spring 30 when the pressure of the finger is released from the cap, as hereinafter explained. 105

The magazine tube 26 is a plain straight cylindrical tube having a snug but sliding fit within the exterior casing 20, and said magazine tube 26 has at its upper end the sleeve 25 which is rigid with the tube 26 and has a somewhat enlarged upper portion 43 which is split to have a spring action and receives a plug 44 of rubber or the like. The plug 44 closes the upper end of the magazine. The enlarged portion 43 of the cap 25 tightly receives with a friction fit the cap 21. The sleeve 25 is normally spaced from and above the upper edges of the exterior casing 20, as shown in Fig. 1, and hence the sleeve, cap 21 and magazine 26 may be moved forwardly or toward the lower end of the casing 20 by pressure applied on the outer end of the cap 21, the space between the lower edge of the sleeve 25 and upper edge of the casing 20 being provided to permit of the reciprocating movement of said magazine, sleeve and cap. 115

The lower end of the magazine tube 26 is closed by the base member or plug 27 whose upper portion tightly fits the lower end of 120

the magazine tube and whose lower portion shoulders against the lower edge of said tube as clearly shown in Figs. 2 and 3. As hereinbefore described the upper surface of the base member or plug 27 inclines downwardly toward its center and merges into the vertical opening 32 through which the leads, one after another, are allowed to pass, said leads by reason of the formation of the upper surface of the base member or plug 27 automatically finding their way to the opening 32 and passing thence into the collet 30.

The collet 30 is tubular and screwed into the threaded socket 31 formed in the base member or plug 27, and the bore of said collect is concentric with the vertical opening 32 in said base member or plug 27. Throughout about one-half of its length, this being the upper or rear half, the collet 30 is a plain straight tube. The lower or forward portion of the collet 30 is tubular and split to form spring arms 45 whose lower portions are thickened and have outer surfaces which incline downwardly and outwardly and inner surfaces formed with gripping surfaces 46. By reason of the construction of the lower ends of the arms 45, said ends, which I number 47, perform wedge functions, as hereinafter explained. The arms 45 are adapted to be closed toward each other for the purpose of gripping the lead, as shown in Fig. 1, and to automatically spring outwardly from the lead when permitted so to do, as shown in Fig. 2. The arms 45 at their wedge ends 47 are adapted to slide outwardly or toward the rear over the stick of lead without engaging the same, but when the magazine and collet are pressed forwardly by pressure applied to the cap 21, said arms grip the stick of lead and propel the same forwardly until the collet reaches its forward limit of travel whereupon said arms automatically release the stick of lead, the lead then having been projected forwardly for writing purposes.

The lower portion of the collet 30 is within the interior chamber of the fitting or base member 35, and the upper end of said fitting or base member 35 receives the nut 34 which has a vertical bore, a threaded portion which enters the fitting or base member 35 and a head which seats against the outer or rear edge of said base member or fitting 35, as clearly shown in Figs. 2 and 3. The collet 30 extends through the nut 34 and is free of said nut. The base member or fitting 35 seats within the lower or forward portion of the exterior casing 20 and is stationary in said casing. Between the nut 34 and the base member or plug 27 of the magazine tube 26, is positioned the coiled spring 33 whose tension acts to press the fitting or base member 35 against its

seat and the magazine 26 and its parts outwardly or in a direction toward the rear. The coiled spring 33 permits the cap, magazine and collet 30 to be pressed forwardly by a finger applied on the outer end of the cap 21, said spring then compressing, and when the pressure of the finger has been relieved from the cap 21, the spring 33 restores the magazine, collet and cap to their outer position, shown in Fig. 1.

Within the chamber 37 of the fitting or base member 35 is loosely placed the sleeve 36, the walls of whose bore incline downwardly and outwardly, thereby creating a wedge within the sleeve. The outer walls of the sleeve 36 are plain and straight and freely slidable on the walls of the chamber 37. The sleeve 36 encompasses the lower portion of the collet 30 within the chamber 37. When the spring 33 moves the magazine 26 and collet 30 outwardly or toward the rear, the wedge members 47 of the collet engage the wedge-shaped bore of the sleeve 36 and move said sleeve in an outward or rearward direction until the upper edge of the sleeve becomes arrested on the lower edge of the nut 34, and thereafter during the slight further outward or rearward movement of the magazine 26 and collet 30 under the influence of the spring 33, the wedge members 47 of the collet by sliding against the wedge surface of the bore of the sleeve 36, become squeezed inwardly toward one another and against the stick of lead extending through the collet whereby the collet is caused to grip the lead and maintain such grip due to the said wedge portions being tightly held within the bore of the sleeve 36. When thereafter pressure is applied on the outer end of the cap 21, said cap, the magazine 26, collet 30 and sleeve 36 move forwardly together until the forward or lower edge of said sleeve becomes arrested on the shoulder 38 of the fitting or base member 35, and at this time the sleeve 36 having become arrested the collet continues its forward movement to carry the wedge members 47 from operative engagement with the sleeve 36 and into the chamber 39 formed at the lower end of the chamber 37. When the wedge members 47 enter the chamber 39 and thus become free from the wedging action of the sleeve 36, said wedge members spring or yield outwardly from and release the stick of lead, having by that time propelled the stick of lead throughout the forward stroke imparted to the collet by the pressure of the finger on the cap 21. When the wedge members 47 and sleeve 36 reach their extreme forward position, shown in Fig. 2, the pressure of the finger on the cap 21 is released and thereupon the spring 33 acts to move the magazine tube 26 and collet 30 outwardly and at this time the wedge members 47 of the collet draw the sleeve 36 outwardly un-

til said sleeve becomes arrested against the forward or lower edge of the nut 34, the collet having a slight further outward movement under the influence of the spring 33 after the sleeve 36 has become arrested so that the wedge members 47 of the collet may by wedging against the bore of the sleeve 36 be caused to move toward each other and again grip the stick of lead preparatory to 10 again propelling the lead forwardly when pressure is applied against the cap 21. The lower end of the collet is dished upwardly, as at 48, and the upper exposed end of the stem 24 is beveled downwardly and outwardly, these features of the construction being to insure the outward movement of the wedge members 47 from the stick of lead when said members reach their lower position within the chamber 39 at the base 20 of the chamber 37 (Fig. 2). The wedge members 47 are expected to spring outwardly when they pass below the influence of the wedge sleeve 36, but if for any reason they should not act automatically, the dished 25 surface 48 by engaging the tapered upper end of the stem 24 will assist the wedge members 47 in moving outwardly to free the lead.

The method of assembling the several parts shown in Fig. 10 and Figs. 12 to 14 inclusive may vary, but one convenient method would be to slip the sleeve 36 downwardly upon the collet 30 and then introduce the lower end of the collet, with said 30 sleeve, into the fitting or base member 35, whereupon the nut 34 may be slipped down upon the collet and screwed into the upper end of said fitting or base member 35. The spring 33 may then be slipped downwardly 35 over the collet 30 and the upper threaded end of the collet screwed into the socket 31 of the base member or plug 27 of the magazine tube 26, after which leads 29 having been introduced into the magazine tube, the plug 44 may be inserted into the upper end of the 40 sleeve 25 carried by the upper end of said magazine tube, all the aforesaid parts then being in the condition shown in Fig. 11 and ready to be introduced into the exterior casing 20. After the assembled interior structure shown in Fig. 11 has been introduced 45 into the exterior casing 20, the tip 23 will be applied by inserting the stem 24 upwardly through the lower end of the casing and screwing the same into the threaded opening 40 in the lower end of the base member or fitting 35 until the shoulder 42 on 50 said tip firmly engages the lower edge of said casing 20. The application of the tip 23 to position serves to firmly lock the fitting or base member 35 rigidly within the lower portion of the exterior casing 20. After the interior mechanism has been applied within the casing 20, the cap 21 is 55 pushed downwardly over the sleeve 43 and

plug 44 at the upper end of said casing 20, as shown in Fig. 1.

The operation of the mechanism of the pencil will be largely understood from the foregoing description. One stick of 70 lead will automatically slide downwardly through the opening 32 in the base member or nut 27 of the magazine 26 and enter the collet 30, passing downwardly to the wedge portions 47 thereof, then in their upper position shown in Fig. 1. Pressure will then be applied upon the outer end of the cap 21 to force the collet downwardly into the chamber 39 at the lower end of the chamber 37 so that the wedge members 47 80 may spread apart and permit the lead to pass between them and into the tip 23. Thereafter the pressure on the cap 21 is released and the spring 33 restores the magazine tube 26 and collet 30 to their outer position, in arriving at which the wedge members 47 will grip the stick of lead, as shown in Fig. 1, and thereupon if the cap 21 is pressed downwardly again, the members 47 will force the lower end of the stick of 85 lead outwardly from the tip 23 so that the same may be used for writing purposes, as shown in Fig. 2. Immediately upon the lead being projected in the manner shown in Fig. 2 pressure on the cap 21 will be 90 released to permit the magazine tube 26 and collect 30, with the sleeve 36, to return to their upper position shown in Fig. 1, in which position the members 47 will again grip the stick of lead and hold the 95 same stationary during the use of the pencil. The repeated reciprocation of the cap 21, magazine tube 26 and collet 30 as the 100 end of the stick of lead becomes worn off, will finally result in the stick of lead becoming so short as not to be engaged by the members 47 of the collet 30, and at this time a further stick of lead will descend from the magazine tube 26 against the upper end of the short piece of lead 105 then held within the tip 23. The reciprocating movement of the cap 21 and collet 30 will cause this new stick of lead to be moved downwardly by intermittent movements against the short piece of lead in 110 the tip 23, until finally the short piece of lead will become fully ejected from the lower end of said tip and be followed up by the lower end of the new stick of lead 115 being exposed for writing purposes.

A very desirable feature of the construction described is that after the pencil has been used for writing purposes and it is desired to return the pencil to the pocket, downward pressure may be applied on the 120 cap 21 to release the gripping members 47 of the collet from the lead, whereupon the projecting portion of the lead may be pushed back into the tip 23.

The invention is not limited to all the 125

details of form and construction hereinbefore described, since I am aware that some of such details may be modified without departure from my invention and within the scope of the appended claims.

What I claim as my invention and desire to secure by Letters-Patent, is:

1. A mechanical lead pencil including a casing having a tip at its lower end for guiding and supporting a piece of lead, a tubular collet slidably mounted within the casing, said collet being provided at one of its ends with a plurality of spring arms having relatively long inner gripping surfaces between which the piece of lead passes, and means for causing the collet to alternately grip and release the lead to propel it step-by-step as the collet is reciprocated in the casing.
2. A mechanical lead pencil as claimed in claim 1, in which said spring arms have outer inclined or wedge surfaces, and in which the means for closing said arms against and, thereafter releasing them to free the lead comprise a slidable sleeve having a wedge bore encompassing said arms, a shoulder for arresting said sleeve on its outward movement with said arms before said arms complete their movement, whereby the wedge surfaces of the arms are moved against the wedge surfaces of the then stationary sleeve and said arms are thereby caused to close against the lead, and a shoul-

der for arresting said sleeve on its forward movement in binding relation with said arms before said arms cease their movement, whereby said arms travel beyond the influence of said sleeve and free themselves from the lead.

3. A mechanical lead pencil including a casing having a tip at its lower end for guiding and supporting a piece of lead, a tubular collet slidably mounted within the casing, said collet being provided at one of its ends with a plurality of spring arms having inner gripping surfaces between which the piece of lead passes, the outer surfaces of said spring arms being tapered outwardly and downwardly, a clamping ring encircling the spring arms, said clamping ring being movable with the collet and having a wedge bore complementary to the tapered outer surfaces of the spring arms whereby to normally hold the spring arms in gripping engagement with the lead, means for reciprocating the collet, and means for limiting the movement of the clamping ring to a shorter stroke than that of the collet whereby to cause the alternate gripping and releasing of the lead as the collet is reciprocated.

Signed at New York city, in the county of New York and State of New York this 20th day of November, A. D. 1924.

ABRAHAM POLLAK.
